(Design.)

No 24

Geo. W. Simons. Pencil Case.

Patented Nov. 18 1844.

Dec. 24

Geo. W. Simons, Philadelphia, Pennsylvania
Letters Patent No. 24, dated November 18th 1844

The Schedule referred to in these Letters Patent and
making part of the same. —

To all whom it may concern: Be it known that I,
George W. Simons of the City of Philadelphia in the State
of Pennsylvania, have manufactured an Ever Pointed
Pencil case, of a new shape or configuration, and I do
hereby declare that the following is a full and exact des-
cription thereof.

In manufacturing my pencil cases, I take a sliding
case of any of the usual forms, and through this sliding
case, I cut two slits or longitudinal openings which are di-
stributed on opposite sides of such sliding case. These slits
I cover by means of a sliding shield, which embraces the
case above named, fitting closely to it, but sliding freely on
it. Such shield I make sufficiently long to enclose the
slits, so that they will not be visible when the shield is
either slid up or down. Through the centre of the sliding
shield, I pass a screw which is tapped into it, and into
the barrel within the sliding case, its shank passing through
the two slits in said case.

In the accompanying drawing, fig. 1. is a representation
of the configuration of the pencil case with the shield
in place; a, a, is the sliding case, b, b, the shield, and
c, the screw that passes through it. Fig. 2. represents the
instrument without the sliding shield, this and the screw
having been removed; d, is the minor barrel, shown through
the slit e, there being a similar slit on the opposite side.

The shape or configuration, which I claim as new

and original, consists in the so forming of the sliding case, as that it shall have two slits made through it, opposite to each other; that there shall be a sliding shield fitting on to the sliding case, and of such length as that it shall cover the slits in the sliding case, whether slid up or down, and that a screw or pin, answering a like purpose, shall pass through and be made fast in the sliding shield; shall also pass through the slits in the sliding case, and through the barrel, by which shape or configuration a neat and convenient article is produced, which may readily be taken apart and cleaned, and in which the barrel that carries the pencil point is supported by a pin on both sides, and is thereby made more permanent, and slides more pleasantly and evenly than when supported on one side only.
